UNITED STATES PATENT OFFICE

95,881

DESIGN FOR A LAMP-POST OR SIMILAR ARTICLE

Ralph Waggoner, Los Angeles, Calif., assignor to Marbelite Corporation of America, Ltd., Los Angeles, Calif., a corporation of Delaware

Application March 18, 1935, Serial No. 55,911

Term of patent 14 years

To all whom it may concern:

Be it known that I, Ralph Waggoner, a citizen of the United States, residing at Los Angeles, in the county of Los Angeles and State of California, have invented a new, original, and ornamental Design for Lamp-Post or Similar Article, of which the following is a specification, reference being had to the accompanying drawing, forming part thereof.

Fig. 1 is an elevation of a lamp post showing my new design;

Fig. 2 is a bottom plan view of Fig. 1.

I claim:

The ornamental design for a lamp-post or similar article, as shown.

RALPH WAGGONER.
